UNITED STATES PATENT OFFICE.

ALBERT E. WALDEN, OF BALTIMORE, MARYLAND.

OZONE-GENERATOR.

1,050,260.

Specification of Letters Patent. Patented Jan. 14, 1913.

Application filed October 23, 1912. Serial No. 727,395.

To all whom it may concern:

Be it known that I, ALBERT E. WALDEN, a citizen of the United States, residing at Baltimore, in the State of Maryland, have 5 invented certain new and useful Improvements in Ozone-Generators, of which the following is a specification.

This invention relates to improvements in ozone generators.

10 The invention consists of the novel construction and arrangement of the parts and combination of parts hereinafter more fully set forth in the following specification and pointed out in detail in the claims.

15 In the accompanying drawings,—Figure 1 is a vertical sectional view of my invention. Fig. 2 is a bottom plan view of the dielectric and the inner electrode. Fig. 3 is a modification of my invention.

20 Referring to the accompanying drawings, forming part of this specification, and in which like reference numerals designate like parts throughout the several views, 1 designates a shell constructed of iron, or other 25 suitable material, and provided with metal partitions 2 and 3, and partitions 4 and 5 of insulating or other suitable material, forming the compartments 6, 7, 8 and 9. Within the shell 1 is a cylindrical electrode 10 having 30 its ends secured to the metal partitions 2 and 3, through which the electric current passes to the said electrode 10, and having communication with the compartments 7 and 9. Within the outer electrode 10 is an 35 inner electrode consisting of two tubes 11 and 12, the latter being closed at its lower end and its upper end being open and communicating with the compartment 7. The tube 11 projects through the partition 4, and 40 is held in position thereby, and has its upper end open to the compartment 6, the lower portion of the said tube 11 projects down into the tube 12 and is open at its lower end. This tube 11 is also provided with one or 45 more openings 13 leading to the compartment 7. The tubes 11 and 12 are held to their proper relative position by the pins 14 or other suitable means. Between the outer electrode 10 and the tube 12 of the 50 inner electrode is a dielectric 15 of glass, micanite or other suitable material, the upper end of which is open and projects into the compartment 7, the lower end of said dielectric 15 is also open and projects into the 55 compartment 9. The said dielectric 15 rests on the cross-bar 16 of insulating material

which is secured to the lower end of the rod 17, the upper end of which latter is secured to the bottom of the tube 12 of the inner electrode. The said dielectric 15 is held in 60 its proper relative position by the star-shaped piece 30, which may be of any suitable material. The electric current is applied to the inner electrode and to the shell 1 through the wires 18 from any suitable 65 source of supply.

The compartment 8 is provided with an inlet 19 and an outlet 20 through which water, or other suitable cooling medium, passes to and from said compartment, for 70 the purpose of maintaining a suitable temperature therein. The compartment 6 is also provided with an inlet 21, through which the air to be ozonized enters, and the compartment 9 is provided with an outlet 75 22 through which the ozonized air is conveyed away for any desired purpose and in any suitable manner.

The operation is as follows: Water, or other suitable cooling medium, passes 80 through the inlet 19 to the compartment 8 and out through the outlet 20, thus maintaining a suitable temperature in the said compartment. A current of electricity of the desired frequency and potential is applied through the wires 18 to the shell 1 and the inner electrode comprising the tubes 85 11 and 12. The air to be ozonized enters the compartment 6, through the inlet 21, and passes down through the tube 11 to the tube 90 12, then up between said tubes 11 and 12 to the compartment 7, then down between the tube 12 of the inner electrode and the outer electrode 10 on both sides of the dielectric 95 15 to the compartment 9 from which point the ozonized air passes through the outlet 95 22 and is conveyed away for any desired purpose and in any suitable manner. Again, only a portion of the air may be 100 passed to the bottom of the inner electrode, the remaining, or any other suitable portion, passing out through the opening or openings 13 in the top of the tube 11 direct to the compartment 7, and then in both cases from the compartment 7 to the compartment 9, 105 from which point it may be conveyed away for any desired purpose and in any suitable manner. These methods of passing the air, or other gas, through the apparatus, provide a method of controlling the temperature of the inner electrode by varying the 110 size of the opening, or openings, 13, or by

omitting said openings, in the tube 11 and thereby preventing oxidation, corrosion and the formation of nitrate of aluminum, or any other aluminum compound.

In Fig. 3 I have shown a modification in which I employ three compartments 23, 24 and 25, instead of the two shown in Fig. 1. In this modification the outer electrode opens to the compartment 23, the outer tube 12^a of the inner electrode opens into the compartment 24, and the inner tube 11^a opens to the compartment 25. Air or other cooling medium enters the chamber 24 through the inlet 26 and passes down between the tubes 11^a and 12^a of the inner electrode and up through the inner tube 11^a to the compartment 25, where it is discharged through the outlet 27. The air to be ozonized enters the compartment 23 through the inlet 28 and passes down on both sides of the dielectric 15^a between the inner and outer electrodes 12^a and 10^a, where it is ozonized and passes to the compartment 9^a.

By the use of generators constructed in accordance with my present invention, the air or other gas to be ozonized can be enriched with oxygen, or other suitable gas, derived chemically or otherwise, and also by means of sodium peroxid, and of its compounds or suitable forms, or by other chemicals giving a suitable gas to be added to the air or gas to be ozonized, thereby enriching or controlling the ozone product in any manner.

Having thus described my invention, what I claim is:

1. In an ozone generator the combination of an outer shell, or casing, divided into a plurality of compartments, an outer electrode secured in one of said compartments and having communication with the compartments next above and below, an inner electrode projecting into the outer electrode and having communication with the two upper compartments, the lower end of said inner electrode being closed, and a dielectric between the inner and outer electrodes.

2. In an ozone generator the combination of an outer shell, or casing, divided into a plurality of compartments, an outer electrode secured in one of said compartments and having communication with the compartments next above and below, an inner electrode having communication with the upper compartment and projecting down into the outer electrode and having its lower end closed, and a dielectric secured between the inner and outer electrodes and open at its upper and lower ends.

3. In an ozone generator the combination of an outer shell, or casing, divided into a

plurality of compartments, an outer electrode secured in one of said compartments and having communication with the compartments next above and below, an inner 65 electrode comprising an inner tube the upper end of which opens to the upper compartment and an outer tube closed at its lower end and into which the lower open end of the said inner tube projects, and a 70 dielectric between the inner and outer electrodes.

4. In an ozone generator the combination of an outer shell, or casing, divided into a 75 plurality of compartments, an outer electrode secured in one of said compartments and having communication with the compartments next above and below, an inner electrode projecting into the outer electrode and having communication with the two upper 80 compartments, two electric wires one of which connects with the outer shell and the other with the inner electrode and both of which lead to a suitable source of supply, and a dielectric between the inner and outer 85 electrodes.

5. In an ozone generator the combination of an outer shell, or casing, divided into a plurality of compartments, the upper one of which is provided with an inlet, the 90 lower one with an outlet and the next to the lower one with an inlet and an outlet, an outer electrode secured in the compartment having the inlet and outlet and having communication with the compartments 95 next above and below, an inner electrode projecting into the outer electrode and having communication with the two upper compartments, and a dielectric between the inner and outer electrodes.

6. In an ozone generator the combination of an outer shell, or casing, divided into a plurality of compartments, an outer electrode secured in one of said compartments and having communication with the compartments next above and below, an inner electrode comprising an inner tube the upper end of which opens to the upper compartment and provided with one or more 105 apertures leading to the compartment next 110 to said upper compartment and an outer tube closed at its lower end and into which the lower open end of the said inner tube projects, and a dielectric between the inner and outer electrodes.

In testimony whereof I affix my signature in presence of two witnesses.

ALBERT E. WALDEN.
